CAN PERFORATOR

Claude E. Venne, Tomahawk, Wis.

Application August 18, 1944, Serial No. 549,993

4 Claims. (Cl. 30—16)

1

The present invention relates to can openers and more particularly to those of the perforating or punching type adapted for use on cans containing milk or other liquids.

An object of the invention is to provide a simple and inexpensive can perforator which can be conveniently operated by one hand.

Another object is to provide a can perforator which is stably located in operative position by its cooperation with a can.

A further object is to provide a can perforator having can piercing means which are protected or guarded to avoid damage thereto and to prevent injury to users.

The invention further consists in the several features hereinafter described and claimed.

In the accompanying drawing,

Fig. 1 is a side elevation of a can perforator constructed in accordance with the invention, parts being shown in section and a projected position of the piercing members thereof being shown in dotted lines;

Fig. 2 is a bottom view of the can perforator, and

Fig. 3 is a front elevation of the perforator, parts being broken away and parts being shown in section.

In the drawing, the numerals 10 and 11 designate a pair of relatively movable elongated plates which are connected at their ends by a hinge pin 12 to guide their relative movement, the connected plates resembling a strap hinge. The bottom plate 10 forms a base member and is adapted to rest on the top wall of a can 12 which is to be perforated, the can being of the type containing milk or other liquid. The free end of the plate 10 has a down-turned arcuate flange 13 adapted to bear laterally against the circular rim of the can, so as to position the plate on the can. The radius of the flange 13 is preferably shorter than the radius of the smallest can on which the device is to be used, so that the opposite corners or ends of the flange will engage the can rim and cause the plate 10 to extend diametrically across the top wall of the can, as indicated in Fig. 2. Preferably, an arcuate groove 14 is formed in the bottom wall of the plate 10 along the flange 13 so as to provide clearance for the rim bead 14' present on some types of cans, this bead being shown on the can 12' of Fig. 3.

The top plate 11 normally extends over the bottom plate 10 and is provided with a longitudinally spaced pair of downwardly projecting conically pointed piercing or penetrating members 15 and 16, the members being riveted or otherwise rigidly

2

secured to the plate. If desired, these piercing members may be integral with the top plate. The piercing members 15 and 16 are movable through respective apertures 17 and 18 formed in the bottom plate, the aperture 17 being here shown in the form of a notch which divides the rim-engaging flange 13. The piercing member 15 is adjacent to the flange 13 for punching a pouring opening in the can adjacent to the rim of the can, and the piercing member 16, which is at some distance from the member 15, is adapted for punching a vent opening in the can. A large convexly rounded knob 19 is riveted or otherwise rigidly secured to the top plate at a point approximately midway between the piercing members and is adapted to be struck or pressed by the palm of the hand. The knob also serves to place the device on the can and to remove it from the can.

The hinged plates 10 and 11 are normally retained in spaced relation one above the other by a leaf spring 20 which is secured to the underside of the plate 11, as by the riveted piercing member 15 and the riveted knob 19. One end portion of the spring 20 forms a spring element and has bent tongues 21 which bear on the upper surface of the base plate 10 to urge the plates apart. The other end portion of the spring is bent downwardly to form a retainer and is provided with an inturned lip 22 engageable beneath the end flange 13 of the base plate for limiting the upward movement of the top plate 11. If desired, the base plate flange may have a notch or recess 23 to receive the lip. The normal spacing of the plates is such that the points of the piercing members extend in the base plate apertures but do not project, thus avoiding damage to the points and preventing injury to persons handling the device. In assembling the device, the spring lip 22 is sprung over the base plate flange 13 to place the device in its operative condition. If occasion should arise, the spring lip may be released from the base plate to permit wider separation of the plates.

When the device is to be used it is placed on the top wall of a can, as indicated in Fig. 1, the base plate 10 resting diametrically on the can top wall and the flange 13 engaging the rim of the can so as to position the piercing members. A push or rap by the palm of the hand on the knob 19 will cause the piercing members to penetrate the can top wall, thus forming the pouring and vent openings. The points of the piercing members may be arranged for either simultaneous or successive initial contact with the can top wall.

Upon release of manual pressure the spring 20 will retract the piercing members from the can, permitting the device to be lifted free of the can. During the use of the device only one hand is required, it being unnecessary to use the other hand either to guide the device or to steady the can.

The device can be manufactured at a relatively low cost, the parts being few in number and being of simple construction. When the device is in use the knob is only a short distance above the base plate, thus insuring stability when the piercing pressure is applied.

What I claim as new and desire to secure by Letters Patent is:

1. A can perforator comprising a base member adapted to rest on the top of a can, a piercing member movable in an up-and-down direction and adapted to puncture the top wall of the can, a supporting arm for said piercing member movably swingably carried by said base member, and a retainer for limiting the outward swing of said arm and forming a guard for said piercing member.

2. A can perforator comprising a base member adapted to rest on the top of a can, a piercing member movable in an up-and-down direction and adapted to puncture the top wall of the can, a supporting arm for said piercing member swingably carried by said base member, spring means for retracting said piercing member from its hole-forming position, and a stop member carried by the free end portion of said arm and engageable with said base member for limiting retraction of said arm, said stop member being releasable to permit further separation of said arm from said base member.

3. A can perforator comprising a base member adapted to rest on the top of a can, an arm extending above said base member for up-and-down movement and hingedly secured to said base member, and a pair of spaced downwardly projecting piercing members carried by said arm and adapted to puncture the top wall of the can, said piercing members being at different distances from the hinge axis of the arm, and said arm having a manual pressure knob thereon between the piercing members.

4. A can perforator comprising a pair of hingedly connected upper and lower plates, the lower plate forming a base member adapted to rest on the top of a can, a downwardly projecting piercing member carried on the upper plate and adapted to puncture the top wall of the can, and a leaf spring having a portion urging said plates apart and another portion limiting the separating movement of said plates.
